CLAIM

The ornamental design for a timepiece face, substantially as shown and described.

DESCRIPTION

FIG. 1 is a front view of my invention;

FIG. 2 is an elevation view thereof;

FIG. 3 is a top elevation view thereof;

FIG. 4 is another elevation view thereof;

FIG. 5 is a bottom elevation view thereof;

FIG. 6 is a rear view thereof;

FIG. 7 is a front view of a second embodiment of my invention;

FIG. 8 is an elevation view thereof;

FIG. 9 is a top elevation view thereof;

FIG. 10 is another elevation view thereof;

FIG. 11 is a bottom elevation view thereof; and,

FIG. 12 is a rear view thereof.
